A. ROBERTS.
AUDIBLE CULINARY ALARM.
APPLICATION FILED AUG. 26, 1915.

1,175,816.

Patented Mar. 14, 1916.

UNITED STATES PATENT OFFICE.

ADA ROBERTS, OF YERKES, PENNSYLVANIA.

AUDIBLE CULINARY ALARM.

1,175,816.

Specification of Letters Patent. Patented Mar. 14, 1916.

Application filed August 26, 1915. Serial No. 47,544.

To all whom it may concern:

Be it known that I, ADA ROBERTS, a citizen of the United States, residing at Yerkes, in the county of Montgomery and State of Pennsylvania, have invented certain new and useful Improvements in Audible Culinary Alarms, of which the following is a specification.

This invention relates to an audible culinary alarm or signaling device of the common hour-glass type and has for its object to increase the scope and delicacy of adjustment of such articles to more completely meet the individual judgment and taste of any particular housewife, said object being accomplished by the construction, arrangement and combination of parts hereinafter more particularly set forth and described.

In the accompanying drawings: Figure 1 represents a perspective view of an alarm embodying my invention; and Fig. 2 represents a cross-sectional view of the hour-glass slightly above the narrowest part of its communicating passage or neck.

Referring now in detail to the drawing, 1 designates a supporting frame of a single piece of wire having a horizontal lower rod 2 from which the alarm bell 3 is suspended. Extending upward from this rod 2 it is 30 twisted on itself to form bearings 10 for the arms 4 of the yoke 5. From the bearings 10 the frame extends upward and backward at a slight angle and is U-shaped in form to provide a rest for the stem of the 35 bell-striker or clapper 6.

The hour-glass shaped emery container 7 is mounted in any suitable manner in wire frame 8 consisting of one piece of wire, which is soldered to yoke 5 at their points 40 of intersection, one of the ends of the wire of said frame being carried up and bent slightly forward, forming a stem to receive fixedly on its tip the striker 6, holding the same slightly in advance of the longitudinal 45 central line of the hour-glass, thus making it slightly top heavy. Stops 9 are fixed on the arms 4 to bear against the inner faces of the bearings 10 and prevent the arms 4 from slipping out of said bearings.

When a sufficient quantity of emery has 50 passed from the upper part *a* of the hour-glass to the lower part *b* to cause the hour-glass to assume a vertical position, the striker 6 will be slightly in advance of the 55 vertical central line of the hour-glass, mak-

ing it top-heavy and causing it to turn on its arms 4 in bearings 10, thereby bringing the striker 6 into contact with bell 2 and sounding the alarm. The position of parts *a* and *b* of the hour-glass will then be inverted and the emery or other suitable material will flow back into part *a* from part *b*, when the device will be ready for use again.

The hour-glass container 7 is provided, at its narrowest part 15 of the passage between the two members *a* and *b*, with a transverse slot and, to regulate the flow of emery from part *a* to part *b*, a plate 11 is pivotally mounted at the narrowest part 15 of the passage between these two parts in 70 said transverse slot by means of a rivet 12 passing through a lug 13 on the exterior face of the hour-glass at this point, this lug being divided by said transverse slot in which the plate oscillates. This plate 11 is 75 provided with a regularly tapering arcuate slot 14 adapted to be brought under the narrowest part of the passage at 15, as shown in Fig. 2. The length of this slot 14, as shown in Fig. 2, is five times the diameter of the passage at its narrowest point 15, and the maximum width of the slot 14 is equal to the diameter of said passage at said point.

The top of the exposed part of the plate 85 11 is provided with a series of five numerals and the edge of the upper part of lug 13 is brought to a fine line to act as an index, thus when the plate 11 is moved by arm 16 so that numeral 1 registers with the thin 90 edge of the lug 13 it will indicate that the plate is in position to allow the maximum flow, when the numeral 5 so registers it will indicate that the plate is in position to allow only the minimum flow, and when registering with intermediate numerals will indicate that the plate is between these two extremes. As this arcuate tapering slot 14 is one continuous opening it will be evident that the plate may be set so that the 100 thin edge of lug 13 will register with any one of the numerals or may be set at any desired point between any two numerals to secure any desired rate of flow within the range of the slot 14, thus securing a great 105 degree of delicacy in the adjustment. Also, if desired, after the hour-glass has turned on its arms 4 so as to bring part *b* uppermost, the flow of the emery may be expedited by turning the plate 11 until the thin 110

edge of lug 13 registers with numeral 1 to allow the maximum flow of material from *a* to *b*.

Any suitable materials may be used for 5 any of the parts above described and they may be fashioned or shaped of any desired number of pieces and assembled in any suitable, convenient and desired manner. I prefer however to use celluloid for the hour-glass container or some other light, transparent or nearly transparent non-frangible plastic material.

Minor changes may be made in the construction, combination and arrangement of 15 the several parts of my invention, of which only a preferred form is shown and described herein, without avoiding the spirit thereof, and it is my intention to include all such in the appended claim which it is 20 my desire shall be given the broadest construction consistent with its wording.

Copies of this patent may be obtained for five cents each, by addressing the "Commissioner of Patents, Washington, D. C."

Having thus described my invention, what I claim as new and desire to secure by Letters Patent is:

In culinary alarms, an integral hour-glass, a pivotally mounted plate oscillating in a transverse opening in said hour-glass at the narrowest point of the passage between the two parts of the latter, provided with a tapering arcuate slot and adapted to be oscillated to bring any desired part of said slot into register with said passage, and means integral with said hour-glass and between which the plate is secured for oscillatory motion.

In testimony whereof, I have signed my name to this specification in the presence of two subscribing witnesses.

ADA ROBERTS.
